UNITED STATES PATENT OFFICE

WILLIAM JARVIS COOK, OF CLEMMONS, NORTH CAROLINA

METHOD OF REENFORCING CORRUGATED CARDBOARD

Application filed April 16, 1931. Serial No. 530,676.

This invention relates to packing cases and more particularly to an improved mode of reenforcing packing cases of the corrugated paper board type.

5 An object of the invention is to provide an improved corrugated type paper carton with reenforcements so arranged as to greatly increase its strength and durability and permit the handling of more weighty 10 objects with safety.

The invention consists in the novel construction, arrangement and combinations of parts as well as the improved method herein more particularly described and claimed.

15 Two sheets of drawings accompany this specification as part thereof, in which like reference characters indicate like parts throughout.

Figure 1 is a plan view of the improved 20 carton blank unfolded with the reenforcement members in position.

Figure 2 is a perspective view of the carton after the initial folding operation.

Figure 3 is a perspective view of the improved 25 carton with the folding operation carried one step further.

Figure 4 is a perspective view of the carton with one end sealed.

Figure 5 is an exploded perspective illustrating 30 the arrangement of the reenforcement members as they would appear in the completely folded carton.

Figure 6 is a fragmentary longitudinal cross section view on a large scale illustrating 35 the position of the reenforcement members in the body of the carton.

Figure 7 is an enlarged fragmentary transverse cross section taken on line 7-7 40 of Figure 6.

In accordance with the present invention, the carton blank is of a generally rectangular shape with the corrugations extending transversely of its long axis. Numeral 1 45 identifies the carton blank as an entirety, which carton is divided transversely by three crease lines 5 and longitudinally by two crease lines also identified by numeral 5.

Slots 4 are provided in continuation of the 50 transverse crease lines dividing side wall

members 2 and front and back wall members 3.

The reenforcement members which are preferably of wire, are arranged in groups adjacent to and on each side of the transverse fold lines and adjacent each of the ends of the carton. These reenforcement wires 55 are preferably threaded through the corrugations of the corrugated part 9 disposed between the face sheets 8-8 of the carton 60 board as is well illustrated in Figures 6 and 7.

With the structure thus defined, it will be apparent that when the carton is folded along the transverse fold lines 5, as illustrated 65 in Figure 2, the reenforcement members will be arranged in groups closely adjacent each of the corners of the carton. When the ends are folded in as illustrated 70 in Figures 3 and 4, the reenforcement wires 75 will be crossed adjacent the corners of the carton, thus providing maximum reenforcement and strength at these, the most vulnerable points of the package. In large cartons, if desired, additional reenforcement 75 members 7 may be inserted intermediate the larger side panels as illustrated.

Obviously, each group of reenforcement members can consist of any desired number 80 of reenforcement wires, as will be dictated by the particular weight of the object to be packed and various modifications of the arrangement will suggest themselves to those skilled in the art within the scope of the 85 present invention.

The invention particularly lends itself to a very simple method of application as the reenforcement wires can be readily threaded 90 through the corrugations of standard box 90 cartons where desired.

The wires or some of them are preferably sufficiently long to project at each end beyond the box board and these opposed ends 95 may be twisted together as at 10, which will materially strengthen the carton. Where the contents of the box are of particular value, a seal 11 may be used in connection with such interlocked wires. 100

Having thus fully described my invention,
I claim:

1. A carton blank adapted to be folded on transverse lines to form side walls and on longitudinal lines to form top and bottom parts in which the blank is formed of corrugated board with the corrugations extending transversely of the blank with a plurality of reinforcement members positioned in said corrugations adjacent to, on each side of, and spaced from, each of the transverse folding lines and each end edge.
2. The method of reinforcing corrugated paper cartons which consists in threading wires through the corrugations parallel with, adjacent to, and on each side of, the fold lines.
3. The structure of claim 1 in which the reinforcement members are wires greater in length than the carton blank so that the opposed ends of said wires will project beyond the edges of the carton blank.

In testimony whereof I affix my signature.
WILLIAM JARVIS COOK.
